UNITED STATES PATENT OFFICE.

GEORGE R. SCHOENTHALER, OF CHICAGO, ILLINOIS.

SUPPORT AND TIE FOR CONCRETE-REINFORCING BARS.

1,132,735.

Specification of Letters Patent.

Patented Mar. 23, 1915.

Application filed May 31, 1913. Serial No. 771,116.

To all whom it may concern:

Be it known that I, GEORGE R. SCHOENTHALER, a citizen of the United States, residing at the city of Chicago, county of Cook, State of Illinois, have invented a certain new and useful Improvement in Supports and Ties for Concrete-Reinforcing Bars, of which the following is a full, clear, and exact description, such as will enable others skilled in the art to which it appertains to make and use the same, reference being had to the accompanying drawings, forming part of this specification, in which—

- 15 Figure 1 is a perspective view of a combined reinforcing bar, support and tie of my improved construction. Fig. 2 is a side elevational view of the combined support and tie seen in Fig. 1, and showing the same associated with a pair of crossed reinforcing rods. Fig. 3 is a perspective view of a modified form of the combined support and tie, the same being constructed wholly of wire. Fig. 4 is a side elevational view of 20 the form of combined support and tie seen in Fig. 3; the same being associated with a pair of crossed reinforcing rods. Fig. 5 is a perspective view of a further modified form of the combined support and tie. Fig. 6 is a side elevational view of a combined support and tie of the form seen in Fig. 5, the same being associated with a pair of crossed reinforcing rods. Fig. 7 is a perspective view of a further modified form of 25 the combined support and tie. Fig. 8 is a horizontal sectional view taken through the central portion of the modified form of support and tie illustrated in Fig. 7. Fig. 9 is a perspective view of a further modified form of the combined support and tie. Fig. 10 is a vertical section taken through the center of a combined support and tie of the form illustrated in Fig. 9 and showing the device associated with a reinforcing rod.
- 40 My invention relates generally to reinforced concrete construction, and more particularly to a support and tie for the metal rods or bars used in reinforcing concrete floors, ceilings, walls and like structures.
- 45 My present invention is an improvement upon the combined support and tie disclosed in an application for patent filed by me April 4, 1913, Serial No. 758,837, and should be read in connection with a copending application filed by me May 31, 1913, Serial No. 771,115.

In reinforcing concrete floors, ceilings, and walls, it is desirable and in nearly all instances essential that the reinforcing rods be supported in a plane above or away from the temporary flooring or form upon which the concrete is laid, and to this end I have devised a comparatively simple, strong and inexpensive one piece support and tie, which can be readily associated with the reinforcing rods, and which will tie the same together and support them a substantial distance above the floor or form while the concrete in plastic condition is being poured or distributed thereupon.

The principal object of my invention is to provide a combin'd support and tie which, when properly applied, will automatically grip and engage the supported rod or rods to effectively hold the same in proper position, and which support and tie is constructed so that the gripping action upon the rods is obtained by reason of the weight of said rods, which weight acting upon the support and tie causes the same to perform the functions of a lever with one end resting upon the surface of the false work or form and with the other end gripping the supported rod. Where the combined support and tie is utilized in connection with a pair of crossed rods, the upper portion of the device grips the upper one of the rods while the lower rod forms a fulcrum for the device.

Other objects of my invention are: to form a combined support or chair from wire or sheet metal, which can be readily cut and bent to proper shape; to provide a device which can be readily combined with the reinforcing rods as the same are laid out upon the flooring or false work and which device will effectively hold the rods against lengthwise movement, and, further to provide a device which is practically skeleton in form and around which the plastic concrete will readily flow so that the device is wholly embedded in the concrete when the same has become set and hardened.

With the above and other objects in view, my invention consists in certain novel features of construction, and arrangement of parts, hereinafter more fully described and claimed.

In the form of device illustrated in Fig. 1 the combined support and tie is formed from a single piece of sheet metal, the same being

2

approximately rectangular in blank form, and one end portion of the piece of sheet metal constitutes a vertical leg 10, the lower end of which is preferably notched as designated by 11, so as to form points 12 at the lower corners of said leg, which points engage in the false work or form upon which the concrete is laid, thereby anchoring said device and preventing the same from shifting laterally after being properly positioned. The section of material from which the device is formed is bent downward from the upper end of the leg 10 to form a comparatively short leg 13 which is approximately half the length of the leg 10 and the upper portions of the legs 10 and 13 are notched or cut away as designated by 14 to form a seat for one of the reinforcing rods. The section of material of which the device is formed is bent from the lower end of the leg 13 into semi-circular form to provide a seat 15 for the lower one of the reinforcing rods and from this seat the section of material forming the device is bent upward and outward to form an inclined leg 16, the same being notched or cut away from one side to form an opening 17 which is in horizontal alinement with the notches or cut away portions 14. The end 20 of the section of material at the upper end of the inclined leg 16 is bent downward as designated by 18 and the lower edge of this downwardly bent portion is adapted to engage on top of the upper one of the supported reinforcing rods when the device is properly applied thereto. In applying this form of support and tie to a pair of crossed reinforcing rods, said rods are lifted a short distance away from the false work or form 25 after which the combined support and tie is applied to the upper rod A by manipulating said device so that said rod occupies the notch 17. The device is now moved toward the opposite rod B and at the same time said device is swung upward so that the lower one of the rods B engages in the seat 15 and the upper rod A engages in the notches or cut away portions 14. The rods A and B are now permitted to move downward until the 30 points 12 on the lower end of the leg 10 engage the false work or form and the weight of the rods transmitted through the device causes the same to perform the functions of a lever and automatically bring about a gripping action of the device upon both rods. The device fulcrums upon the lower rod B and the edge of the downwardly bent portion 18 engages and grips the top of the upper rod A and said rod A bearing upon the lower rod B holds the same firmly in its seat.

In the form of device illustrated in Figs. 3 and 4, said device is constructed from a single piece of wire bent to proper shape and comprising a short vertically disposed

leg 19, the lower end of which is bent to form a skeleton foot 20, which is horizontally disposed and adapted to rest upon the false work or form. From the upper end of the leg 19 the section of wire is bent downward and outward to form a curved seat 21 which is adapted to receive the lower one of the reinforcing rods, and from this seat the section of wire is bent upward to form an inclined leg 22 which occupies an angle of approximately 45° relatively to a horizontal plane and the upper end of this inclined leg is bent upwardly and thence downwardly to form a curved hook 23 which when the device is applied for use engages over the upper one of the reinforcing rods. In this form of the device the weight of the supported rods acting through the device causes the same to perform the functions of a lever, the same utilizing the lower rod as a fulcrum and gripping and tying together both rods in the same manner as heretofore described in connection with the device illustrated in Figs. 1 and 2.

The device illustrated in Figs. 5 and 6 is constructed from a single piece of sheet metal bent to form a pair of parallel side legs 24, and a pair of parallel end legs 25. The legs 24 in this device are inclined when the device is properly associated with a pair of rods, and one of said legs is approximately half the length of the other. Formed in the tops of the legs 24 are notches 26 which receive the lower one of a pair of crossed rods and the upper one of said rods engages in a notch 27 formed in the underside of the upper one of the end legs 25. The lower edge of the lower end leg 25 is notched or cut away as designated by 28 so as to form points 29 at the lower corners of the device, which points are adapted to engage the flooring or false work to anchor the device and hold the same from slipping upon the flooring or false work when in service.

In the form of the device illustrated in Figs. 7 and 8, the combined support and chair is formed from a single piece of sheet metal comprising a main body portion 30, which occupies an inclined position when applied to the reinforcing rods, and the central portion of this body is notched from one side as designated by 31, to accommodate and form a seat for the lower one of the supporting rods. The lower end of this portion of the body 30 is notched or cut away as designated by 32 to form anchoring points 33 which engage with the false work or form to prevent the device from slipping while in use. The upper end of the body 30 is bent outwardly and downwardly to form a curved seat 34 which, when the device is applied for use engages over the upper one of the supporting rods. The body 30 is reinforced by a vertically disposed

stiffening rib 35, which is pressed or stamped from the material of which the device is formed.

The device illustrated in Figs. 9 and 10 is similar to the device illustrated in Figs. 7 and 8, but it is intended for use in connection with a single reinforcing rod, and where such construction is carried out the upper end of the body of the device is bent 10 downward as designated by 36 and the lower edge of this bent portion is notched as designated by 37, to provide a seat for the supported rod.

The forms of devices illustrated in Figs. 15 3 to 10 inclusive differ slightly in structural details, but are the same in principle as the form of device illustrated in Figs. 1 and 2, inasmuch as all the modified constructions 20 utilize the weight of the supported rods for effecting a gripping of said rods, and the consequent tying together of a pair of crossed rods.

Devices of my improved construction are very simple, can be cheaply manufactured, 25 can be readily combined with reinforcing rods, and any one of the various forms of the device when properly applied performs the functions of a lever.

The gripping action of the device on the 30 supported bars is obtained by the weight of the bars reacting through the support, which latter fulcrums upon the lower one of the supported bars and transmitting the resulting reaction through leverage to the upper 35 per bar, consequently tying the two bars together, and supporting the same in a substantial manner the desired distance above or away from the surface of the false work or form upon which the concrete is laid.

40 It will be readily understood that minor

changes in the size, form and construction of my improved support and tie can be made and substituted for those herein shown and described, without departing from the spirit of my invention, the scope of which is 45 set forth in the appended claim.

I claim:

A device of the class described formed of a single piece of metal and comprising a supporting member adapted to be applied to 50 a pair of crossed reinforcing rods, said member being provided with a seat for the lower one of the rods, which seat is located a substantial distance to one side of the point of contact between the lower end of 55 the supporting member and the floor or form on which the device is positioned, said member being open at one side above the seat for the lower rod to accommodate the upper one of the reinforcing rods, the upper 60 end of said supporting member being provided with a single bearing which is located above and a substantial distance to one side of the seat for the lower one of the rods, and which bearing is adapted to engage the top 65 of the upper one of the reinforcing rods, which construction permits the supporting member to tilt and occupy an inclined position when applied to the reinforcing rods, thereby gripping said rods by the reaction 70 of the weight of said rods through the support.

In testimony whereof I hereunto affix my signature in the presence of two witnesses, this 27th day of May, 1913.

GEORGE R. SCHOENTHALER.
